POWDER DISPENSING CAN

John Glover, Chicago, Ill., assignor, by mesne assignments, to Midway Chemical Co., Jersey City, N. J., a corporation of New Jersey

Application June 29, 1936, Serial No. 87,905

9 Claims. (Cl. 221—61)

This invention relates to powder shipping and dispensing containers.

Among the objects of my invention is to provide a shipping and dispensing container for powdered material of the type wherein the body is provided with a collapsible bellows for forcibly projecting powder through the container nozzle and wherein the interiors of the container and the nozzle are constructed so that powder may be 10 expelled from the nozzle in any position in which the container is held.

Another object of my invention is to provide a simple type of means for insuring the forcible expulsion of the powder from the container nozzle in any position in which the container is held.

These and other objects of the invention will be apparent from a perusal of the following specification when taken in connection with the accompanying drawing, wherein

20 Figure 1 is a perspective view of a preferred construction of the shipping and dispensing container, the improvement being shown in dotted lines.

Figure 2 is a front elevational view with the 25 front wall broken away.

Figure 3 is a plan sectional view taken on the line 3—3 of Figure 1.

Figure 4 is an enlarged sectional view taken on the line 4—4 of Figure 1.

30 Figure 5 is an enlarged sectional view taken on the line 5—5 of Figure 1.

Figure 6 is a perspective view of the funnel, and

Figure 7 is a sectional view taken on the line 7—7 of Figure 5.

35 Figure 8 is a vertical sectional view taken on the line 8—8 in Figure 3.

Referring now to the drawing in detail, I have illustrated the invention as applied preferably to a sheet metal can having a front 2 and a back 4 40 preferably provided with longitudinally extending end walls 8 of curved contour. The front, back and side walls are preferably formed of a single plate of metal seamed together at one of the curved sides as is well known in the art.

45 The container is provided with a top 10 and a bottom 12, both of which are seamed to the main body of the container in a well known manner as shown at 14 and 16 in Figures 4 and 5. Either the front or back of the container is provided with 50 a collapsible bellows type of device for forcibly expelling the powdered contents of the can.

The invention herein is not in the specific form of collapsible bellows construction except as to the manner in which the same enters into combination with the can and the nozzle construc-

tion. Briefly stated, the front wall of the can is provided with an opening 18 in which is mounted a bellows device 20 including a presser plate 22, a flexible diaphragmatic portion 24 and a spring 26 located within the can and adapted normally to press the plate or abutment 22 outwardly. As is well known, by pressing relatively quickly inwardly on the bellows, the powdered content of the can is adapted to be expelled from the can nozzle 28, the marginal walls 32 of the opening 10 in the top 10 being imbedded in a groove formed in the nozzle. This nozzle construction may be of any desirable construction but I preferably form it in the manner shown in Figure 4, wherein the nozzle base 30 is relatively thick and provides 15 a smooth inner bore 34 through which the powder is adapted to be expelled. The upper end of the nozzle is threaded as at 36 for the reception of a cap 38.

20 My present invention provides means for feeding the powdered material to the nozzle 28 in any position of the can, whether it be normally upright, sideways or upside down. Heretofore in cans not provided with my invention, it has been necessary to tip the can relatively upside down 25 to cause a proper expulsion of the powder. If the can were held sideways or normally in upright position the powder would not be expelled. However, with my present invention, irrespective 30 of the position of the can, upon squeezing the bellows, the powder, which is always in position to be expelled, will be forcibly ejected from the nozzle 28.

35 In the present form of my invention I provide an extension nozzle from the nozzle 28 substantially to the base of the can or container. This extension nozzle comprises a tubular conduit 40 preferably of sheet metal, although not necessarily, which is securely fastened as at 42 within the base of the tubular nozzle 28. The bottom end of the nozzle is open and is preferably formed on a diagonal bias as at 44 whereby to permit the powdered contents of the can to flow easily into the funnel-like mouth of the nozzle or tubular conduit 40.

45 Instead of spotwelding, soldering or otherwise affixing the base of the nozzle 40 as at 46 to the can wall 8, I prefer to affix it in position in the manner set forth in Figure 5 wherein the extension nozzle 40 is provided with a preferably arcuate extension or tip 48 which is placed in position in registration with the lower end of the can wall 8 so that in the seaming operation the extension 48 to form the seam and likewise to hold the bottom of the nozzle in position.

It will be understood that my invention is not limited to the cross-sectional dimensions of the can nor to the shape of the can, but is adapted to any general shape of container and may take other forms, provided they are embraced within the scope of the appended claims. It is also obvious that the container may be made of paper or other suitable material.

When the can is upright the powder at the bottom will always tend to flow into the funnel-shaped bottom 44 of the sleeve 40, thus filling the extension nozzle 40 so that a direct charge 15 of this powder is always in position to be projected by the air in the can compressed by the bellows mechanism. Therefore, irrespective of the position of the can, powder will always be fed to the outside nozzle.

20 Having thus described my invention what I claim as new and desire to be secured by Letters Patent is as follows:

1. A shipping and dispensing container for powdered material, comprising a tubular body 25 wall having opposed substantially flat end closures secured thereto, one of said closures having an opening closed by a removable cap for filling and refilling said container, a powder dispensing nozzle carried in one of said end closures, 30 means for sealing said nozzle to prevent deterioration of the container contents and accidental dispensing of the same, said body wall having a cut-out portion defined by an annular bead and a clamping ring, and a bellows member disposed 35 within said container for ejecting said contents through said nozzle when said sealing means is removed, said bellows member including a flexible diaphragm having its marginal portion secured between said annular bead and said clamping 40 ring.

2. A dispensing container having side walls and a collapsible bellows formed in one of said walls, said container having a nozzle through which powdered contents within the container are 45 adapted to be expelled upon the operation of the bellows, said nozzle having a tubular extension projecting from a point adjacent the bottom of the container directly to the nozzle and open to the interior contents of the container, said nozzle 50 being of substantially funnel-shaped dimensions, said nozzle also having its lower end cut on a diagonal line to facilitate the entry of the powdered contents into the nozzle.

3. A can having a body portion, a top, and a 55 bottom and having a nozzle, the body portion being provided with a collapsible bellows, a top for the body portion, a bottom seamed to the body portion, and a funnel extension having a portion extending adjacent to the bottom and 60 held in place by the bottom seam.

4. In a container of the bellows type, the combination of a can having a main body portion and a bottom seamed thereto, said can having a top, and a nozzle projecting therefrom, said can having a tubular nozzle extension, the bottom of the extension extending into the bottom seam of the can.

5. A dispensing can of the bellows type comprising a main body portion, a top, and a bottom,

seams uniting the body portion, the top, and the bottom, the body portion having a collapsible bellows device, the can having a nozzle through which powdered material in the can may be expelled, said nozzle having a tubular extension, 5 said extension being rigidly held in position within the container by means of one of the seams of the can.

6. A shipping and dispensing container for powdered material comprising a tubular body 10 having opposed end closures secured thereto, a powder dispensing nozzle carried in one of said end closures, said body having a cut out portion defined by an annular bead and a clamping ring, and a bellows member disposed within said container 15 for ejecting said contents through said nozzle when said sealing means is removed, said bellows member including a flexible diaphragm having its marginal portion secured to said annular bead and said clamping ring. 20

7. A shipping and dispensing container for powdered material comprising a longitudinally extending, tubular body having substantially opposed, parallel, flat side walls joined by curved connecting walls along their longitudinally extending side edges, opposed end walls secured respectively to the opposite ends of the tubular body and being arranged transversely thereof, a powder dispensing nozzle carried by one of the end walls, bellows means in one of said flat side 30 walls for ejecting said contents through the nozzle upon inward movement thereof, and spring means mounted between said side walls and acting upon said bellows for normally urging said bellows means outwardly. 35

8. A shipping and dispensing container for a powdered material comprising a tubular body having opposed end closures secured thereto, a powder dispensing nozzle in the end of one of said end closures, said nozzle having a tubular 40 extension projecting from a point adjacent the bottom of the container directly to the nozzle and open to the interior contents of said container, said body having a cut out portion defined by an annular bead and a clamping ring, and a 45 bellows member disposed within said container for ejecting said contents through said nozzle when said sealing means is removed, said bellows member including a flexible diaphragm having its marginal portion secured to said annular 50 bead and said clamping ring.

9. A shipping and dispensing container for powdered material comprising a tubular body having opposed flat side walls and opposed end closures secured respectively to the opposed open 55 end of said tubular body, a powder dispensing nozzle carried by one of said end closures, said nozzle having a tubular extension projecting from a point adjacent the bottom of the container directly to the nozzle and open to the interior 60 contents of said container, bellows means in one of said side walls for ejecting said contents through said nozzle upon inward movement thereof when said sealing means is removed, and spring means between said side walls and acting upon said bellows means for normally urging said means outwardly. 65

JOHN GLOVER.
